UNITED STATES PATENT OFFICE.

AUGUST SUNDH, OF HASTINGS UPON HUDSON, NEW YORK, AND WILLIAM WESTERMAN, OF DETROIT, MICHIGAN.

INDICATOR FOR MILLS.

Application filed October 8, 1920. Serial No. 415,512.

To all whom it may concern:

Be it known that we, AUGUST SUNDH, a citizen of the United States, and a resident of Hastings upon Hudson, county of Westchester, and State of New York, and WILLIAM WESTERMAN, a citizen of the United States, and a resident of Detroit, county of Wayne, and State of Michigan, have invented certain new and useful Improvements in Indicators for Mills, of which the following is a specification.

This invention relates to a device to be applied to mills for indicating the travel of a moving part of the mill, the device also being adapted to indicate the amount of material passing through the mill at any time.

In general, the invention relates to a device particularly adapted for application to a rolling mill, an object of the application of this device to a rolling mill being to indicate the peripheral travel of a roll of the rolling mill and to indicate also the amount of material which is passed through the mill.

Another object of the invention is the provision of a device of the character designated which is automatically controlled, means having been provided whereby the device is set in operation by the energization of a relay energized by current drawn from the line by an electric motor which is employed for driving the mill.

A further object of the invention is the provision of a device of the character designated wherein the indicating element for indicating the travel of a roll of the rolling mill will be set in operation as soon as the rolls of the mill begin to rotate and wherein in the other indicating element if not indicating the amount of material passed through the mill, will remain idle until the material is fed to the mill.

In the accompanying drawings wherein an embodiment of our invention has been illustrated,—

Fig. 1 shows in part sectional elevation the device applied to a rolling mill;

Fig. 2 is a front elevation of the apparatus shown in Fig. 1;

Fig. 3 is an enlarged view of the indicating element and part of the driving means therefor; and

Fig. 4 shows on an enlarged scale a mag-

netizable element adapted to be driven by 55 a roll of the mill and which element constitutes a driving element for both indicating elements.

Referring now to the drawings in detail, 1 and 2 designate respectively the upper 60 and lower rolls of a rolling mill to which our device is applied. It is to be understood, however, that the device forming the subject-matter of this invention is capable of use with other than rolling mills if desired. The rolls 1 and 2 are supported for rotation in side frames 3 and are driven by an electric motor 4, the armature shaft of which carries a small spur gear 5 meshing with a large gear 6 connected in the usual 70 way to the rolls 1 and 2 of the mill. The motor 4 receives its current from a source of electrical supply 7, the circuit for the motor being controlled by the usual switch 8, resistance 9 having been provided in the 75 motor circuit as is customary. The metal to be rolled is conveniently supported on brackets 10 at one side of the machine, the metal here having been designated 11. As pointed out above, however, it is to be understood that the present invention is not to be limited to the application of our improved device to a mill of this character for 80 rolling metal as obviously the device is applicable to other types of machines. 85

Supported by one of the side frames 3 is a casing 12, this casing being supported by brackets 13 and 14 immediately above the upper roll 1 of the mill. Carried within the casing 12 at the upper part thereof in 90 the present instance, are indicating elements 15 and 16 respectively, the indicating element 15 being adapted to register or indicate the peripheral travel of the roll 1 while the indicating element 16 is adapted to register or indicate the amount of material, that is to say metal 11, passed between the rolls 1 and 2. Inasmuch as the particular type of indicating element, 15 or 16 as the case may be, does not form any part of the 95 present invention, we have deemed it unnecessary to show the details of construction thereof, inasmuch as any of the well-known forms of indicator now on the market are adapted for use in connection with 100 our device.

Within the casing 12 and supported by a bracket 17 therein is a rotatable, mag-

netizable or electrically controlled element or device 18 shown on an enlarged scale in Fig. 4. This element is adapted to engage or be engaged by the upper mill roll 1 and 5 is provided for the purpose of driving the indicating elements 15 and 16. This element is provided with a winding 19 and receives current from the source of power 7 in a manner which will be hereinafter 10 pointed out. The element 18 is provided with a shaft 20 mounted in bearings 21 and 22 in the bracket 17, this shaft carrying at one end a rotatable member 23 cooperating with contacts 24 and 25 and carrying at its 15 other end a bevelled gear 26. The gear 26 is in constant mesh with a bevelled gear 27 mounted upon a vertically extending shaft 28, this shaft being adjustable vertically, relative to a vertically extending shaft 29 20 in alinement therewith and carrying adjacent its upper end bevelled gears 30 and 31. The gear 30 meshes with a bevelled gear 32 carried upon a shaft 33, this shaft carrying one portion of a cone-clutch or electrically 25 controlled device 34 presently to be described. The gear 31 is in constant mesh with the bevelled gear 35 carried upon a shaft 36, the latter constituting a driving or actuating means for the indicating 30 elements 15. It will be seen, therefore, that we have provided means including the magnetizable element or clutch 18 for operatively connecting the motor 4 to the indicator 15. The clutch 34 already referred 35 to, comprises two portions 37 and 38, the member 37 being rigidly mounted upon the shaft 33 already referred to, while the member 38 is mounted upon and has longitudinal movement relative to a shaft 39 connected to the indicating element 16 and 40 adapted to drive the same. The clutch 34 is electrically controlled, being provided with a winding 40 which when energized will cause the member 38 to move into 45 clutching position relative to the member 37 so that if at that time the gear 32 and therefore the shaft 33 be rotating the shaft 39 will be driven to drive the indicating element 16. The winding 40 of the clutch 34 50 is adapted to receive current from the source of supply 7 and for this reason is provided with contacts 41 and 42 and collector rings 43 and 44.

The electrically controlled element 18 is 55 adapted to be adjusted with respect to the casing 12 vertically thereof, being secured to the casing by members 45 passing through slots 46 in the bracket 17. This adjustment is provided so that the element 18 may 60 always be in engagement with the mill roll 1. As heretofore pointed out the shafts 28 and 29 are adjustable relative to each other, being coupled together at 47 so that when the bracket 17 is adjusted either up or 65 down the shaft 28 will be carried with it.

This ensures that the gear trains will always be in mesh and the indicators 15 and 16 driven.

The wiring for our device is indicated in Fig. 1 from which it will be seen that the 70 motor 4 receives its current from a supply 7 when the switch 8 is closed, the current passing through the motor from the positive side of the line by way of conductor 48, resistance 9, initially, conductor 50 through the motor, conductor 51, winding 52 of a relay 53, conductor 54 to the negative side of the line. The closing of the switch 8 also closes a circuit to the winding 19 of the magnetizable element 18, this circuit being 75 from the positive side of the line by way of conductors 55 and 56, contact 24, collector ring 23 through the winding 19, collector ring 23', contact 25, conductor 57, winding 52 of the relay 53, conductor 54 80 to the negative side of the line. The winding 19 being energized, the element 18 will adhere to the roll 1 of the rolling mill so that the latter will drive the former and through the gears 26, 27, 30 and 31 drive 85 the indicating element 15. The circuit for the winding 40 of the clutch 34 is at this time open and therefore the indicating element 16 is not functioning. As soon, however, as the metal 11 is fed to the rolling 90 mill, the increased load on the motor 4 will cause the latter to draw an increased current from the line so that the winding 52 of the relay 53 will be sufficiently energized 95 to cause the relay 53 to function and lift a contact 58 into position to bridge stationary contacts 59 and 60. A circuit for the winding 40 of the clutch 34 will now be 100 closed, which circuit may be traced as follows: From the positive side of the line 7 by way of conductors 48, 55, 61, 62 through the winding 40, conductor 63, contacts 59, 58 and 60, and conductor 64 to the negative side of the line. The energization of the winding 40 will cause the member 38 of the 105 clutch 34 to travel into clutching position relative to the clutch member 37 so that the indicating element 16 will now be driven also to register the amount of material 110 passed through the mill, the drive for this indicating element being from the shaft 20, gears 26 and 27, shafts 28 and 29, gears 30 and 32, through the clutch 34 to the indicating element. The relay 53 will maintain 115 its contact 58 in position to bridge the contacts 59 and 60 so long as the extra load on the motor 4 due to the strip 11 passing through the mill is maintained, but as soon as the strip has passed entirely through the mill and the load is therefore relieved on the motor 4, the relay 53 will automatically 120 drop this contact 48 to open the circuit of the winding 40 of the clutch 34 so that although the rolling mill may continue to be driven the indicating element 16 will not 125 130

function while the indicating element 15 will continue to function, to register or indicate the peripheral travel of the mill roll 1. It will be seen, therefore, that the 5 clutch 34 is controlled by the motor 4 in that the current drawn from the line due to the increased load on the motor when a strip is fed through the mill causes the clutch to function to operatively connect the indicator 10 16 to the mill.

From the foregoing it will be seen that we have provided a device adapted to be applied to a mill, which device is capable of registering the travel of a moving part 15 of the mill and which device is also capable of registering the amount of material passed through the mill, the indicating element for registering the travel of the moving part of the mill, however, being operable independently of the other indicating element. This results in a device which is capable at all times of registering the travel 20 of some moving part of the mill and also one capable of registering the amount of 25 material passed through the mill when the same is in operation.

It will be apparent also that we have provided a device of the character described in detail wherein the indicating element for 30 registering the amount of material passed through the mill is under the control of the motor by which the mill is driven and is automatic in its operation.

It will be obvious also that means have 35 been provided for driving the indicating element whereby no slippage will occur between the mill roll and the element driven thereby which in turn drives the indicators, so that the indicators will always register 40 accurately.

It is to be understood that while we have illustrated herein a particular embodiment 45 of our invention, we are not to be limited to the exact details of structure so illustrated and herein described as obviously changes may be made therein within the purview of our invention.

What is claimed is:

1. In combination, a mill, means for indicating the amount of material passed 50 through said mill, an electric motor for driving the mill, a clutch for connecting the mill to the indicator, and means whereby said clutch is electrically connected to said 55 motor to be controlled by the current passing through said motor.

2. In combination, a mill, means for indicating the amount of material passed 60 through said mill, a motor for driving the mill, an electric clutch, connections whereby said clutch is controlled by the current passing through the motor for operatively connecting the indicator to the mill.

3. In combination, a rolling mill, an indicator for indicating the amount of ma-

terial passing through said mill, an electric motor for driving said mill, an electrically-operated clutch for said indicator, means whereby said clutch is operatively connected to said motor, including means whereby the 70 clutch is operable only upon the increase in current flow due to loading of the motor when material is passed through the mill.

4. In combination, a rolling mill, an indicator therefor, and a clutch interposed between a roll of the mill and the indicator and comprising a winding adapted when energized to clutch the indicator to a roll of the mill to cause the roll to drive the indicator.

5. In combination, a rolling mill, a magnetizable roller for engaging a roll of said mill, an indicator for said mill operatively connected to said roller, and means for energizing said roller to cause the same to be 85 driven by the mill roll to thereby drive the indicator.

6. In combination, a rolling mill, an indicator for said mill and driven thereby, a connection between said mill and indicator 90 whereby the same may be adjusted relative to each other, said connection comprising two relatively adjustable shafts, means operatively connecting said shafts, a motor for driving the mill, and an electrically-operated means for connecting one of said adjustable 95 shafts to the indicator, the other of said shafts being operatively connected to the mill whereby said indicator is connected to said mill.

7. In combination with a mill, an indicator for indicating the travel of a moving part of said mill, an indicator for indicating the amount of material passed through said mill, a magnetizable member permanently 100 operatively connected to the first-named indicator and operatively connected to said mill to cause the first-mentioned indicator to function, and an electrically operated clutch for connecting the second-named indicator to the mill to cause the second-named indicator to function.

8. In combination, a mill, an indicator therefor, a motor for driving said mill, a circuit for said motor, and a relay in said 115 circuit for controlling said indicator, said relay being automatically operable to cause the indicator to function, only by the excess current passing through the motor when the mill is being driven under load by said 120 motor.

9. In combination, a mill, an indicator therefor, an electric clutch, a relay, a motor for driving said mill, said relay being controlled by the load on said motor and in turn 125 controlling said clutch, and a drive shaft which is adapted to be connected to said indicator by said clutch.

10. In combination, a mill, an indicator therefor, an electric motor for driving said 130

mill, a drive shaft, an electric clutch for connecting the indicator to the drive shaft, a magnetizable element for connecting the drive shaft operatively to the mill, and a relay controlled by the current passing through said motor for closing a circuit to said clutch.

This specification signed this 23d day of Sept., 1920.

AUGUST SUNDH.

This specification signed this 27th day of Sept., 1920.

WM. WESTERMAN.
